UNITED STATES PATENT OFFICE

OSKAR BORNHAUSER, OF FRANKFORT-ON-THE-MAIN, GERMANY

PHOTOGRAPHIC FILM PICTURE AND PROCESS OF PRODUCING THE SAME

Application filed September 10, 1928, Serial No. 305,066, and in Germany October 3, 1926.

This invention relates to photographic film pictures and process of producing the same; and particularly to apparently drawn film pictures and films commonly referred to as "trick films". The invention finds its particular usefulness in its adaptation to moving picture films, although by no means limited thereto.

An object of the invention is to produce films of the character described, in a unique and highly satisfactory commercial manner enabling rapid and economical production; and in the novel and unique process employed to produce the same.

Other and more specific objects and advantages of the invention will more fully appear from the following description taken in connection with the accompanying drawing illustrating by way of example the preferred product and the method of producing the same.

The invention consists in the novel product herein described and in the novel process for producing the same hereinafter described in accordance with certain preferred embodiments thereof, and the invention will be more particularly pointed out in the appended claims.

Referring to the drawing:

Fig. 1 is a greatly enlarged diagrammatic illustration of various cross sections of progressive steps in the process of producing a film,

Fig. 2 illustrates a strip of negative film of the object photographed,

Fig. 3 illustrates a positive of Fig. 2 after treatment,

Fig. 4 illustrates the positive film of Fig. 3 after further treatment,

Fig. 5 illustrates a further step in the treatment after the positive has been blackened to produce a photographic mask,

Fig. 6 illustrates a composite film negative comprising the mask of Fig. 5 and the original negative,

Fig. 7 illustrates a positive print made from Fig. 6,

Fig. 8 illustrates the film of Fig. 7 after being colored, and

Fig. 9 is a diagrammatic illustration similar to Fig. 1 illustrating the manner of producing colored positive films.

With reference to the drawing, and more particularly Fig. 1: a negative 1 is made of the desired object and comprises dark parts

1a and light parts 1b, representing respectively the area of the object image, and the clear film field. This negative (see also Fig. 2) is then printed on a chromatized and silvered positive film 2, i. e. a film which has been silvered and treated with chromate. While this printing may readily be done from the front face of the film 2, in view of the fact that the gelatin is only 1 to 2/100 of a millimeter; nevertheless as is well understood by those skilled in the art, printing may be done from the bottom side of the film through the support of the same if desired. The positive 2 is then coated with a thin coat of varnish thereby resulting in a positive 3 on which the object is nearly invisible and whose dark parts 3a are hardened and are nearly insoluble in a given bath, such

for example as hot water, and whose light parts 3b are unhardened and are relatively more soluble. The film 3 is then treated in hot water until it loses all unhardened parts, such as 3b, with their silver; whilst the parts such as 3a remain as a positive relief of halogen silver. The film in this stage is illustrated as 4 with the relief of halogen of silver designated as 4b. This stage is also shown in Fig. 3. The surface of the film 4 is prepared afterwards or directly during bathing with a covering impermeable by the

fixing bath. This protective coating may be effected by pouring over the film a dilute varnish solution; or by bathing the film in a soap solution, in which latter case a chrome soap that is difficult to wet is thus precipitated.

tated upon the exposed places, which contain chromium hydroxide. This results in placing a coating 5c on the film designated as 5.

5 The film 5 is then treated for a suitable time in a fixing bath and as a result the silver halide disappears everywhere where the fixing bath has access, i. e. at the edges indicated as 6d on the film 6 (Fig. 1). The 10 smallest parts of the relief portions are entirely dissolved as well as a small zone at the contour of the object image, such as at 6d, resulting in an image as shown in Fig. 4. The coating designated as 5c (Fig. 1) is removed, such for example as by washing away or 15 dissolving it by benzene or other suitable solvent. The result is designated as 7 in Fig. 1, and it will be noted with reference to Fig. 4 that the film presents a halogen silver positive without any details of the fine tracings 20 which have remained up to this point as fine lines within the outline of the image (Fig. 3), and with the light parts 7a a little greater in area than the corresponding homologous parts of the original negative.

25 The positive thus produced is preferably blackened as by treatment with a developer and results in a photographic mask designated as 8 (Fig. 1) and illustrated in Fig. 5, 30 presenting a positive whose images such as 8a correspond in shape and position to those of the negative, but are somewhat larger, and which no longer manifest any detail tracings. This mask is then made to coincide 35 with the original negative, such as by means of the marginal perforations, thus resulting in a composite negative 9 (Figs. 1 and 6) in which the images on a dark ground are edged by a delicate outline 9a, with all 40 the fine tracings easily visible through the mask. The mask positive and original negative are then preferably united in register, as by cement.

45 From this composite negative as many positives, such as 10 (Fig. 7), may be produced as are desirable, by means of the usual copying procedure. Such positives comprise an image in line tracing simulating a delicately drawn image, and the outline of 50 which is designated as 10a. In Figs. 6 and 7 the outlines or contours of the images designated respectively as 9a and 10a are greatly exaggerated in order to clearly indicate their presence.

55 If desired the film may be colored either as to the lines, the background, or both. In such event the positive print, such as 10, should be made on a chromate film, and in 60 tinting or coloring the film the following process has been found satisfactory, although the hereinbefore described process is of course adapted to be used as above described to produce films as illustrated in Fig. 7, and may 65 also be used in connection with other or

further steps as will be well understood by those skilled in the art.

The process of coloring as hereinafter described is based upon the well known property of layers containing chromate, that they become insoluble upon exposure to light. This property alone, however, is not sufficient to give the desired results, since by prior or subsequent coloring of the chromate layer in the usual manner the resultant film consisted of light and dark areas, but no line contours were thus produced. By the present process only the contours or edges of the chromate layer are tinted; while the large areas themselves, whether light or dark in the negative, remain untinted, i. e. contiguous borders between light and dark areas only are tinted on the corresponding positive.

Referring more particularly to Fig. 9: the composite negative 9 (Fig. 6), diagrammatically illustrated on an enlarged scale in Fig. 9, is printed from onto a positive chromate unsilvered film 11. This results in a nearly invisible positive 12 with soluble and insoluble gelatin parts. The film 12 is coated, either before or after development, with a surface coating nearly impenetrable by hot water, thereby presenting a film as indicated as 13 with a covering indicated as 13a. One suitable means of providing such a coating on the surface of the film is by bathing the film in a soap solution, in which case a chrome soap which is difficult to wet is thus precipitated on the exposed places, which contain chromium hydroxide, resulting from the light reduction of the chromate. The film is then put into hot water a sufficient time to dissolve the gelatin parts of the film which have been unexposed to light, i. e. such as 13b, including the covering skin, so that there remains a gelatin relief, whose front surface is covered with a skin impervious to a watery aniline coloring bath. The film at this stage is designated as 14 and the undissolved parts are designated as 14a with the coating of such parts indicated as 14b. The film is then subjected to an aniline color bath containing the desired color to be imparted to the film, and in such bath the color attacks only the edges or contours of the relief portions of the film as at 15a on the film designated at this stage as 15. It will therefore be seen that the marginal edges only of the relief portions are thereby colored. The result of this step produces the film indicated as 16. The duration of the coloring period in the aniline bath may be regulated to limit the coloring to the desired degree of penetration from the side of the relief portions of the film, thereby resulting in producing contours of the desired width surrounding the relief portions of the film. By limiting the coloring treatment, these zones of coloring may be restricted to narrow lines, so that after the film is cleaned, there results only small color contours instead 130

of dark broad parts as present in the ordinary positive. This results in an effect similar to a line drawing and having the desired color outline.

5 After its completion, the film represents an outline drawing consisting of practically colorless layers 16a of chromium hydroxide with a narrow colored border zone 16b and clear celluloid spots 16c. The celluloid portions 16c being free from gelatin may be subjected to independent coloring without detriment or interference with the coloring of the gelatin parts, and vice versa, since the aniline color does not affect the celluloid parts, and 10 the celluloid parts may be suitably colored by a dye bath containing amyl acetate and an addition of oil thereto to thereby entirely prevent the tinting of the chromate gelatin layer. If a colored background is desired, the film 20 may be treated as above explained, resulting in a film such as 17 (see also Fig. 8), in which the celluloid background 17a is colored and the chromate portions 17b remain uncolored but with dark outlines 17c; thereby providing a film 17 on which the images are white with dark outlines on a colored ground. It is also possible to color the gelatin relief portions of the film, in which event the protective layer 16b is rubbed or washed off and the 30 chromate portions designated as 18c are in turn tinted with an independent color, producing thereby the film 18 on which appear colored images 18c with dark outlines 18b and a clear ground 18a.

35 Still another possibility is illustrated in the film 19 (Fig. 9), where the celluloid background 19a and the gelatin relief portions 19c are colored in different colors with darker contour outlines 19b, according to the principles hereinabove described; all of which 40 will be understood by those skilled in the art.

It will be seen that by the present process I have provided means for producing a composite negative from which as many positives as desired may be printed in the usual chemical photographic process and from which also suitable positives in the desired number may be made and said positives may be colored in many ways according to the demand. Since the original negative is made in the usual photographic manner the smoothness of movement of the objects and persons is assured and from this negative corresponding 50 positives may be made according to the herein-described process and in a manner presenting a highly successful commercial manufacture.

55 While the invention is particularly adapted to moving pictures, it is to be understood, as will be appreciated by those skilled in the art, that it is advantageously adapted to the production of "stills" or single pictures. One of such anticipated uses is the preparation of 60 fashion plates and similar photographs,

which character of work lends itself readily to the present invention; and more especially since numerous positives may be made from a single negative.

Having thus described my invention with 70 particularity with reference to the preferred process of carrying out the same, and in connection with the present preferred product resulting therefrom, and having referred to some of the possible modifications thereof, it 75 will be obvious to those skilled in the art, after understanding my invention, that other changes and modifications may be made therein without departing from the spirit and scope of my invention, and I aim in the 80 appended claims to cover such changes and modifications as are within the scope of the invention.

What I claim as new and desire to secure by Letters Patent of the United States is: 85

1. In a photographic negative, the combination of a negative having the usual characteristics of a photographic negative in which the fine lines and tracings of the object image are present, and a photographic mask in superposed and registered position with said negative and in which the silhouette outline only of the object image corresponding to the first negative is present, said silhouette outline being larger than said object image. 95

2. In a photographic negative, the combination of a negative having the usual characteristics of a photographic negative in which the fine lines and tracings of the object image are present, and a photographic mask in superposed and registered position with said negative and in which the silhouette outline only of the object image corresponding to the first negative is present, the image of said mask being larger in outline than the image 100 of said first negative thereby presenting a composite negative in which the said image is outlined by a contour defined by said mask and said negative image, within which outline the fine lines and tracings of the image 105 appear. 110

3. In a moving picture film negative, the combination of a negative having the usual characteristics of photographic negatives in which the fine lines and tracings of the images representing moving objects are present, and a photographic mask bearing transparent images of moving objects homologous to the images of said negative in superposed registration with respectively homologous images of said negative, the images of said mask being larger in area than the respectively homologous images of said negative thereby presenting a composite negative in which the images are outlined as drawn lines within 125 which the fine lines or tracings of the image appear. 120

4. In a moving picture film negative, the combination of a negative having the usual characteristics of photographic negatives in 130

- which the fine lines and tracings of the images representing moving objects are present, and a photographic mask bearing transparent images of moving objects homologous to the images of said negative in superposed to the same and leave intact the hardened parts of the same to thereby produce a positive relief, treating the surface of the relief portions to produce a surface covering impermeable by a fixing bath, subjecting the film to a fixing bath to remove halogen-silver from the accessible sides of said exposed relief, darkening the gelatin portions of the relief unaffected by said fixing bath to thereby produce a negative in the form of a photographic mask, and aligning such mask in proper registered position with the original negative.
5. The process of producing a photographic negative, which comprises taking a negative of the desired object in such manner that details of the object are present on the negative object image in fine lines and the image outline is sharply defined, printing from said negative onto a silvered and chromatized film to produce a positive copy of said negative, dissolving the photographically unexposed parts of said positive to thereby produce a positive relief, entirely removing the halogen-silver from the finer portions of said relief and partially removing the halogen-silver from the contour of the coarser portions of said relief, darkening the gelatin portions of the relief unaffected to thereby produce a negative in the form of a photographic mask, and aligning such mask in proper registered position with the original negative.
10. The process of producing a photographic negative, which comprises taking a negative of the desired object in such manner that fine lines of the object are present, printing from said negative onto a silvered and chromatized film to produce a positive copy, treating the film in a liquid bath to dissolve the photographically unexposed parts of the same and leave intact the photographically exposed parts of the same to thereby produce a positive relief, treating the surface of the relief portions to produce a surface covering impermeable by a fixing bath, subjecting the film to a fixing bath to remove halogen-silver from the accessible sides of said exposed relief, darkening the gelatin portions of the relief unaffected by said fixing bath to thereby produce a negative in the form of a photographic mask, and aligning such mask in proper registered position with the original negative.
15. The process of producing a photographic negative, which comprises taking a negative of the desired object in such manner that details of the object are present on the negative object image, printing from said negative onto a silvered and chromatized film to produce a positive copy of said negative, treating said positive to provide a photographic mask by dissolving unexposed parts and slightly reducing exposed parts of said positive to thereby provide a transparent silhouette of said image homologous to but slightly larger than the image of said negative and suitably treating said positive to provide a darkened field exterior to said silhouette, and aligning such mask in proper registered position with the said negative so that the homologous images thereof are in register.
20. The process of producing a photographic negative, which comprises taking a negative of the desired object in such manner that fine lines of the object details are present on the negative object image, printing from said negative onto a silvered and chromatized film to produce a positive copy having photographically exposed hardened and photographically unexposed unhardened parts, coating the positive with a coating or protective layer, treating the film in a liquid bath to dissolve the unhardened parts of the

same and leave intact the hardened parts of the same to thereby produce a positive relief, treating the surface of the relief portions to produce a surface covering impermeable by a fixing bath, subjecting the film to a fixing bath to remove halogen-silver from the accessible sides of said exposed relief, darkening the gelatin portions of the relief unaffected by said fixing bath to thereby produce a negative in the form of a photographic mask, and aligning such mask in proper registered position with the original negative.

8. The process of producing a photographic negative, which comprises taking a negative of the desired object in such manner that fine lines of the object details are present on the negative object image, printing from said negative onto a silvered and chromatized film to produce a positive copy having photographically exposed hardened and photographically unexposed unhardened parts, coating the positive with a coating or protective layer, treating the film in hot water to dissolve the unhardened parts of the same and leave intact the hardened parts of the same to thereby produce a positive relief, treating the surface of the relief portions to produce a surface covering impermeable by a fixing bath, subjecting the film to a fixing bath to remove halogen-silver from the accessible sides of said exposed relief, darkening the gelatin portions of the relief unaffected by said fixing bath to thereby produce a negative in the form of a photographic mask, and aligning such mask in proper registered position with the original negative.

9. The process of producing a photographic negative, which comprises taking a negative of the desired object in such manner that details of the object are present on the negative object image, printing from said negative onto a silvered and chromatized film to produce a positive copy of said negative, treating said positive to provide a photographic mask by dissolving unexposed parts and slightly reducing exposed parts of said positive to thereby provide a transparent silhouette of said image homologous to but slightly larger than the image of said negative and suitably treating said positive to provide a darkened field exterior to said silhouette, and aligning such mask in proper registered position with the said negative so that the homologous images thereof are in register.

10. The process of producing a photographic negative, which comprises taking a negative of the desired object in such manner that details of the object are present on the negative object image, printing from said negative onto a silvered and chromatized film to produce a positive copy of said negative, treating said positive to provide a photographic mask by dissolving unexposed parts and slightly reducing exposed parts of said

positive to thereby provide a transparent silhouette of said image homologous to but slightly larger than the image of said negative and suitably treating said positive to provide a darkened field exterior to said silhouette, aligning such mask in proper registered position with the said negative so that the homologous images thereof are in register, and printing a positive from said combined negative and positive.

10 In testimony whereof I have signed my name to this specification.

OSKAR BORNHAUSER.
